United States Patent Office

Des. 192,682
Patented May 1, 1962

192,682

BUILDING

Austin E. Cox, Wadsworth, Ohio, assignor to
Garrett A. Brown, Akron, Ohio

Filed Apr. 18, 1961, Ser. No. 64,811

Term of patent 14 years

(Cl. D13—1)

FIG. 1

FIG. 2

Des 192,682

PAGE 2

FIG. 3

FIG. 4

FIG. 5

FIGURE 1 is a front perspective view of a building showing my new design.

FIGURE 2 is a front elevation.

FIGURE 3 is a side elevation.

FIGURE 4 is a rear elevation.

FIGURE 5 is a top plan view.

The door units of FIGURE 4 are lined for color. The platform in FIGURES 1 and 4 are broken away for convenience of illustration only.

I claim:

The ornamental design for a building, as shown and described.
